UNITED STATES PATENT OFFICE.

CROYDEN MEREDITH WHITTAKER, OF CHEADLE HULME, ENGLAND, ASSIGNOR TO COURTAULDS LIMITED, OF LONDON, ENGLAND.

MANUFACTURE AND PRODUCTION OF ARTIFICIAL SILK.

No Drawing. Application filed June 1, 1926, Serial No. 113,107, and in Great Britain July 27, 1925.

When dyeing a number of skeins of artificial silk in the same dyebath, and under the same conditions, it is frequently found that some skeins have absorbed more dye than others, with the result that the skeins are not all of the same shade. This difference in affinity varies according to the dyestuff employed. Wilson & Imison, Journal Soc. Chem. Ind. 1920, p. 323T have pointed out that dyestuffs of high molecular weight tend to produce more uneven shades, while dyestuffs of low molecular weight give more even shades. The difference in affinity for the dye appears to arise from differences in the said silk, which differences are disadvantageous, because when, before being dyed several skeins having such differences between them, are used in making a fabric, this fabric, on being subjected to subsequent dyeing operations, may not be dyed uniformly and some parts appear darker than other parts, and such fabrics may consequently be unsaleable, or much depreciated in value.

There has not hitherto, so far as I am aware, been any way in which the character of artificial silk in this respect can be ascertained before fabrics are made therefrom, and this is very disadvantageous as such silk, in its undyed condition, is a manufactured article put upon the market and sold to manufacturers to make up into fabrics and afterwards dye.

This invention has for its object to overcome this difficulty and to provide quantities of undyed viscose artificial silk the whole of which can be relied upon to have practically equal dyeing affinity. This I effect by taking a quantity of viscose artificial silk in portions which I will refer to as skeins and subjecting all these skeins to a dyeing process for the same length of time with the same bath, using a dyeing agent which tends to produce uneven shades and which is also easily modified so as to become colorless, and afterwards sorting these skeins into batches each consisting of those which have become coloured to the same, or practically the same shade. The dyeing matter is then modified so as to become colorless in the several batches so that separate batches of undyed artificial silk, of practically equal dyeing affinity throughout, are obtained, and, if these batches be afterwards put upon the market and employed separately for the production of fabric, such fabric can be dyed

with the practical certainty (if the dyeing be properly carried out) of obtaining the same shade throughout the fabric, or those parts of a fabric in the making of which the same batch has been used.

Should any single skein itself be composed of two or more parts which become unevenly coloured, such skein would also be removed from the other skeins.

In carrying out the preliminary dyeing according to this invention, use should be made of a dyestuff which can readily be modified so as to become colorless, for example, by bleaching with a dilute solution of sodium hypochlorite, or of calcium hypochlorite, or of hypochlorous acid of sodium hydrosulphite, or any other suitable reducing or oxidizing agent. A list of dyestuffs which tend to give uneven shades on artificial silk is given by Wilson and Imison, and the majority of the dyestuffs mentioned there can be bleached by means of sodium hypochlorite. The following may be mentioned however as particularly suitable for use according to this invention:—

	Color Index No.
Chlorazol fast pink BK	353
Chlorazol sky blue FF	518
Direct blue 2B	406
Direct green G	594

It is advisable to effect the preliminary dyeing of the skeins at a comparatively low temperature, since, as pointed out by Wilson and Imison, a lower temperature tends to enhance the unevenness of the dyeing.

In the term "artificial silk" I include silk whether in the finished state, or in any suitable stage of its production.

What I claim is:—

1. The process for producing batches of viscose artificial silk, the whole of each of which will have practically the same dyeing affinity so that fabrics made therefrom can be dyed to the same shade, the said process consisting in subjecting a quantity of viscose artificial silk in portions, or skeins, to the same dyeing operation using a dyeing agent which is liable to produce uneven shades on batches of viscose artificial silk which are not uniform with each other, which dyeing agent can also easily be modified so as to become colorless, and afterwards sorting these portions, or skeins, into batches each consisting of those which have become dyed,

or colored, to the same, or practically the same, shade and afterwards modifying the said dyeing agent so as to render it colorless, and thereby producing separate batches of undyed artificial silk, each batch of practically equal dyeing affinity throughout.

2. The process of producing batches of viscose artificial silk, the whole of each of which will have practically the same dyeing affinity so that fabrics made therefrom can be dyed to the same shade, the said process consisting in subjecting a quantity of viscose artificial silk in portions, or skeins, to the

same dyeing operation using chlorazol fast pink BK, and afterwards sorting these portions, or skeins, into batches each consisting of those which have become dyed, or colored to the same, or practically the same, shade and afterwards modifying the chlorazol fast pink BK so as to render it colorless, and thereby producing separate batches of undyed artificial silk, each batch of practically equal dyeing affinity throughout.

In testimony whereof I have signed my name to this specification.

CROYDEN MEREDITH WHITTAKER.
